[57] CLAIM

The ornamental design for a combined closure cap and brake fluid dispenser, substantially as shown.

DESCRIPTION

FIG. 1 is a side elevational view of a combined closure cap and brake fluid dispenser showing my new design; FIG. 2 is a rear elevational view; FIG. 3 is a sectional view taken on the line 3—3 of FIG. 2;

FIG. 4 is a side elevational view showing the side opposite that seen in FIG. 1; FIG. 5 is a front elevational view; FIG. 6 is a bottom plan view; and FIG. 7 is a top plan view thereof.

FIG. 4

FIG. 5

FIG. 6

FIG. 7
